LOUIS R. KRUMM, OF NEW YORK, N. Y.

SIGNALING SYSTEM.

Application filed November 2, 1921. Serial No. 512,197.

My invention relates to wireless telegraphy and it has particular relation to signaling systems that are employed in connection with wireless transmission systems.

5 The object of my invention is to provide a signaling system, whereby a source of high-frequency, undamped oscillatory currents may be employed to communicate with receiving stations unable to receive undamped 10 wave signals.

As is well known, the energy radiated by damped-wave systems consists of discontinuous groups of damped oscillatory wave trains of an audible group frequency. The effect of 15 each wave train, upon wave responsive apparatus, is to cause a single click in a telephone receiving device associated therewith.

By reason of the fact that a signal, that is, a dot or a dash, is composed of a number 20 of such impulses, their combined effect is to cause an audible note in the telephone receiving device. The periodicity of the note may be varied by controlling the group frequency at the transmitting station. Receiving systems, which are only responsive to damped 25 wave trains, will hereinafter be referred to as damped receiving systems.

The energy, however, which is radiated by undamped systems, such, for example, as arc- 30 converter systems, is distinguished from that radiated by damped transmitters in that the waves are of uniform intensity during the signaling periods. A signal, therefore, corresponding to a dot or a dash, comprises an 35 unmodulated, undamped wave train which merely causes a click at the beginning and at the end of the signal in the telephone receivers of a damped receiving system.

An undamped wave, in order to be received, must be periodically modulated at an 40 audible frequency. The modulation may be accomplished by any means known to the art, such, for example, as by heterodyning the received impulses with locally generated currents of a slightly different frequency. Receiving systems which are provided with 45 means for periodically modulating the received impulses will hereinafter be referred to as undamped receiving systems.

50 According to my invention, I provide

means whereby the undamped oscillations in sustained-current transmitting systems may be periodically modulated to permit their reception by damped receiving systems.

Briefly speaking, the desired result may be 55 accomplished either by controlling the potential drop across an arc, or by selectively and periodically rendering an absorbing circuit effective or non-effective. My invention is particularly adapted for marine service 60 where the inability of undamped transmitting stations to communicate with damped receiving stations has heretofore required an additional spark-transmitter for emergency work. 65

My invention may best be understood by reference to the accompanying drawings, in 70 which:

Figure 1 is a diagrammatic view of circuits and apparatus embodying my invention. 70

Fig. 2 is a similar view showing a modification of the means for controlling the oscillations in the antenna circuit. 75

Fig. 3 is a similar view showing still another modification whereby the oscillations 75 in the antenna circuit may be selectively controlled.

Referring to Fig. 1, an arc 1 is energized by means of a direct-current source of energy 2 through reactance coils 3, a resistor 4, and blow-out coils 5. An antenna circuit, which is energized by the arc 1, comprises an antenna 6, a variable inductance coil 7, the arc 1, a coupling coil 8 and a ground lead 9. 80

An absorbing circuit, which is operatively 85 coupled to the antenna circuit, comprises a coupling coil 10, a condenser 11 and an energy absorbing element or resistor 12. The resistance of resistor 12 is substantially equal to the total antenna resistance. The condenser 90 11, which is included in the absorbing circuit, is shunted by a circuit which includes a rotary-spark gap or other commutating device 13, and a key 14, and which may include also a resistor 15. While I have shown the arc 1 directly connected in the antenna circuit, my invention is not to be limited thereby, but is 95 equally applicable to systems wherein the arc is inductively coupled to the antenna circuit.

In operation, upon the energization of the 100

arc 1, high-frequency oscillations are caused to traverse the antenna circuit. The period of the absorbing circuit is adjusted to that of the antenna circuit to cause a maximum amount of energy to be absorbed therefrom. Upon closing the key 14, to transmit a dot or a dash, the absorption circuit is periodically detuned to render it effective and non-effective to damp the energy in the antenna circuit at an audible rate corresponding to the speed of the rotary spark gap 13.

In Figs. 2 and 3, I have shown modified arrangements for modulating the energy in the antenna circuit. In the systems therein shown, the modulation is effected by selectively and periodically varying the potential-drop across the arc 1 and the intensity of the transverse magnetic fields of the blow-out coils 16 and 17.

Referring more specifically to Fig. 2, the absorption circuit of Fig. 1 is replaced by a circuit which is shunted around the arc. The circuit just mentioned extends between the direct-current supply conductors 18 and 19 and comprises the pair of auxiliary field coils 16 and 17 a key 19, and a rotating commutator device 20.

The auxiliary field coils 16 and 17 may be either compound or differentially wound with respect to the blowout coils 5, in order that the variations in the intensity of the magnetic field may cause corresponding variations in the stability of the arc. A resistor 21 is employed to limit the passage of currents in the supply circuit during that period in which the potential across the arc is lowered by the closing of the shunt through the auxiliary coils 16 and 17.

In operation, with the key 19 closed, the efficiency of the arc is periodically varied at an audible rate, thereby causing the passage of modulated currents in the antenna circuit. As in the previous figure, the radiation of the modulated energy may be selectively controlled by means of the key 19.

Referring to Fig. 3, the arrangement shown differs from that of Fig. 2 in the provision of means whereby an audio-frequency component of energy may be impressed upon the arc 1 to cause corresponding changes in the arc efficiency.

Briefly speaking, the desired result is accomplished by shunting the blow-out coils 5 with an auxiliary circuit which includes a condenser 22 and a key 23. The capacity of the condenser is tuned to the inductance of the blow-out coils 5 to constitute an audio-frequency circuit, comprising the arc 1, the blow-out coils 5, the condenser 22 and the key 23.

In operation, when the key 23 is closed, the auxiliary circuit oscillates at an audible frequency to periodically vary the drop in potential across the arc 1. The effect of the varying potential-drop across the arc is to cause corresponding modulations in the en-

ergy in the antenna circuit. As in the systems of the previous figures, the radiation of the modulated energy is selectively controlled by means of the key 23.

It will be noted that, when the key 23 is open, the system operates as an undamped-wave transmitter. If desired, the apparatus may be operated altogether as an undamped wave transmitter with the key 23 open, and signals may be formed by any of the well known systems of control, such, for example, as by means of a key (not shown) for shunting a portion of the antenna inductance 7.

The particular advantage of my invention is the provision of improved means whereby an undamped transmission system may be readily modified to permit the transmission of signals therefrom capable of affecting damped receiving systems by periodically modulating the amplitude of the antenna oscillations rather than by varying the periodicity or the wave length of the antenna oscillations as in the present methods.

The systems of control embodying my invention are of especial advantage, however, in marine installations where they admit of the elimination of the spark-gap set which, heretofore, has been essential for the efficient transmission of signals capable of affecting damped receiving systems.

While I have shown three embodiments of my invention, it is capable of various other changes and modifications without departing from the spirit of my invention. I desire, therefore, that only such limitations shall be imposed thereon as are indicated in the appended claims.

I claim as my invention:

1. In a wireless transmission system, an arc, a supply circuit for energizing said arc, means for causing said arc to oscillate, said supply circuit including blow-out coils for producing a transverse magnetic field across said arc, and a condenser shunted around said blow-out coils, the circuit including said condenser and blow-out coils being tuned to an audible frequency, whereby oscillating currents having an audible group-frequency may be established in said arc.

2. In a wireless transmission system, an arc, a supply circuit for energizing said arc, means for causing said arc to oscillate, said supply circuit including blow-out coils for producing a transverse magnetic field across said arc, and a circuit including a condenser and a key shunted around said arc and said blow-out coils, whereby the efficiency of said arc may be varied at a predetermined frequency determined by the tuning of said condenser.

3. In an arc transmitter, a source of current, an arc energized therefrom, means including blow-out magnets for causing said arc to generate high-frequency oscillations and means, energized by energy diverted from said blow-

out magnets, for impressing a low-frequency modulation on said oscillations.

4. In an arc transmitter, a source of current, an arc energized therefrom, means including blow-out magnets for causing said arc to generate high-frequency oscillations, means, energized by energy diverted from said blow-out

magnets, for impressing a low-frequency modulation on said oscillations, and signaling means for controlling said modulating means. 10

In testimony whereof, I have hereunto subscribed my name this 28th day of October, 1921.

LOUIS R. KRUMM.
